(57) **CLAIM**

The ornamental design for a busbar assembly, as shown and described.

DESCRIPTION

FIG. 1 is a first perspective view of the first embodiment of a busbar assembly showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof;

FIG. 9 is an exploded view thereof;

FIG. 10 is a first perspective view of the second embodiment of a busbar assembly;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a second perspective view thereof; and,

FIG. 18 is an exploded view thereof.
